UNITED STATES PATENT OFFICE.

MARK SCHNEIDERMAN, OF NEW YORK, N. Y.

DESIGN FOR A TRUCK TIRE.

Application filed June 24, 1925. Serial No. 13,883. Term of patent 7 years.

To all whom it may concern:

Be it known that I, MARK SCHNEIDERMAN, a citizen of the United States, residing at the city of New York, borough of Brooklyn, county of Kings, and State of New York, have invented a new, original, and ornamental Design for Truck Tire, of which the following is a specification, reference being had to the accompanying drawing, forming part thereof.

Fig. 1 is a perspective view of a portion of a truck tire embodying my new design.

Fig. 2 is a top plan view of the same, and

Fig. 3 is a radial section of a tire showing my new design.

I claim:

The ornamental design for a truck tire as shown.

MARK SCHNEIDERMAN.
